LIQUID AGITATING AND DISPENSING APPARATUS

Robert R. Hull, Covina, Calif., assignor, by mesne assignments, to California Fruit Growers Exchange, Los Angeles, Calif., a corporation of California

Application January 15, 1946, Serial No. 641,267

19 Claims. (Cl. 222—358)

1

This invention relates to liquid dispensing apparatus; and it relates more particularly to apparatus for dispensing a beverage liquid, such as a fruit or vegetable juice, characterized by the provision of power driven means capable of functioning both to agitate a supply of said beverage liquid to a desired extent, more especially continuously, and also, upon appropriate change of driving connection to the source of power, to remove a measured quantity of liquid from said supply into dispensing position.

In dispensing certain kinds of beverage liquids by measuring out and delivering successive portions from a body thereof contained in the supply reservoir, it is desirable in some cases to maintain the body of liquid in such supply reservoir agitated more or less continuously. Not only does this serve to prevent objectionable separation and settling out of pulp or similar solid or semi-solid matter normally contained therein and to keep such matter in suspension and uniformly distributed through the liquid but, in addition, proper agitation has been found effective, in conjunction with refrigeration, to maintain certain juices, notably citrus fruit juice, in good potable condition much longer than when refrigeration alone is relied upon. Whether this is due to the aeration resulting from such agitation, or to some other cause, it is an established fact that if a refrigerated body of orange juice, for example, is maintained properly agitated, the juice will keep sometimes as much as a week or ten days longer than it will when left at rest.

An important object of the present invention is to provide a relatively simple apparatus especially adapted for dispensing beverage liquids of the indicated type, which includes means dependably effective in its operation to maintain a supply body of such liquid adequately agitated and, upon suitable modification of its agitating action, to deliver successive measured portions from said body of liquid to a place of discharge.

A further important object of the invention is to provide dispensing apparatus of the general character stated, in which contact of bearings carrying moving parts with the beverage liquid is eliminated or reduced to a minimum, and which can be kept in sanitary condition and easily recharged with a fresh supply of the beverage liquid whenever necessary.

With these and other objects in view, which will become apparent as the description proceeds, the invention comprises the novel features

of construction and the combinations thereof which will first be described in connection with a practical form of apparatus constituting an illustrative embodiment of the inventive principles involved, and will then be more particularly pointed out in the appended claims.

Dispensing apparatus constructed in accordance with the principles of the invention employs one and the same means operable both to perform the function of agitating the body of beverage liquid contained in the supply reservoir of the apparatus, and also, upon suitable supplemental or modified actuation which may or may not be coin-controlled, to convey from said reservoir a measured quantity of said liquid for dispensing delivery to a point outside the reservoir. Most desirably said means takes the form of a dipper-like device having a hollow stem so mounted for oscillatory movement, and so connected to appropriate driving provision, that the dipper, when the apparatus is not dispensing, depends into the supply reservoir or tank and is swung back and forth close to the bottom thereof, most desirably through a predetermined and positively controlled "agitating" arc of swing, either continuously or to such extent intermittently as may be necessary to ensure agitation of the body of beverage liquid in the desired degree. When a measured portion of liquid is to be dispensed, the action of said driving provision is modified in any suitable manner to cause the apparatus automatically to go through a dispensing cycle, wherein the dipper is caused to swing upwardly beyond its normally limiting position at one end of its "agitating" arc to an elevation such that the measured portion of liquid carried up with it drains from the dipper into and through its hollow stem for delivery outside the reservoir; the dipper being thereupon swung back into the reservoir and continuing to operate in its normal agitating phase until again actuated to go through another dispensing cycle.

Other novel features and advantages of the invention will be apparent from the detailed description hereinafter of one typical practical embodiment of the invention shown in the accompanying drawings, wherein

Fig. 1 is a front elevation of the upper portion of the complete apparatus unit, the apparatus cabinet or housing being shortened vertically and partly broken away to show parts immediately behind the same, and the dipper being indicated in its highest or dispensing position;

Fig. 2 is a top plan of the unit shown in Fig. 1, with the cabinet cover and beverage tank cover removed;

Fig. 3 is an end elevation, partly in section, viewing the apparatus of Fig. 1 from the right and with the cabinet partly broken away, but with the dipper swung down into its lowest position;

Fig. 4 is a plan, on an enlarged scale, of the power and variable transmission unit for operating the agitating and measuring dipper device, looking in the direction of the arrows 4-4 in Fig. 1;

Fig. 5 is a front end elevation corresponding to Fig. 4, but showing certain parts in slightly later operating phase;

Fig. 6 is a front elevation of the gear constituting the driven member of a clutch device included in the transmission unit;

Fig. 7 is a rear elevation of the rotary cam disk for actuating the clutch-shifting mechanism;

Fig. 8 is an elevation of part of the clutch-shifting mechanism, showing the mounting of the cam follower in the clutch-actuating frame or crosshead;

Fig. 9 is a side elevation, partly in central longitudinal section, showing on an enlarged scale further details of how the rotary mounting disk and driving sprocket are assembled and supported for rotation;

Figs. 10 and 11 are, respectively, a rear elevation and a side of said mounting disk showing a portion of the dipper-mounting means secured thereto;

Fig. 12 is a detail perspective showing the co-operating portion of said dipper-mounting means, with the dipper stem secured thereto.

In the beverage dispensing machine illustrated in the drawings, the novel combination of dispensing parts and operating mechanism with which the present invention is primarily concerned is housed as a unit within a cabinet indicated generally at 20. This unit, with its cabinet, is in turn mounted, at a level convenient for beverage dispensing, upon a supporting framework base 21 housed within a cabinet 22. As shown in Fig. 1 more particularly, cabinets 20 and 22 may desirably be so designed and proportioned that they appear, externally, to constitute sections of a single cabinet or housing within which are enclosed not only the main dispensing unit above mentioned, but also any necessary accessories such, for example, as the motor, compressor and condenser of a conventional type of refrigerating unit, indicated generally at 23, located in the base of the lower section of the combined cabinet.

The space within the upper section 20 of the combined cabinet or housing is divided into two unequal portions, front and rear, by a vertically disposed flanged plate 24 which extends the full height of the chamber parallel to the front and rear walls of the cabinet between the opposite side or end walls thereof, being secured to said end walls and to the cabinet bottom in any suitable manner, as by welding. This vertical plate is positioned relatively close to the front wall of the cabinet. Besides thus serving as a partition wall, said plate 24 provides means on which to mount certain apparatus parts and operating mechanism, as will appear hereinafter. For a purpose that will also presently appear, the upper part of the upper cabinet section 20 extends forward to provide an overhanging portion 20a. The cabinet has a double-walled cover 25, hinged as

indicated at 26 along the upper edge of its rear wall 27.

Within the much larger space to the rear of mounting plate 24 is the cooling or refrigerating compartment whose side and bottom walls 28 are covered with a layer of heat-insulating material 29, with which the space between the double walls of cover 25 is also packed. Supported on or adjacent the bottom of the cooling compartment is 10 sealed refrigeration pad 30 containing refrigerant expansion coils (not shown) connected by supply and return pipes 31, 32, to the aforesaid refrigeration unit in the lower cabinet 22.

Nesting within the cooling compartment is the beverage liquid supply tank 33, supported by its outwardly projecting peripheral rim 34 upon horizontal supporting ledges 35 provided on the inner surface of the front and back walls of the cooling compartment a substantial distance 20 below the top of the cabinet. The supply tank is thus supported with its walls and bottom spaced away from the walls and bottom of the cooling compartment. The supply tank is provided with a removable unitary cover comprising a flat main portion 36 and a portion 37 at the front which extends upwardly to provide a housed space within which the dipper device may swing upwardly into dispensing position, as will appear more fully hereinafter. The cover unit 36-37 has a depending peripheral flange 38 fitting snugly within the supply tank rim. The supply tank is provided interiorly with hand grips 39 whereby, after the hinged cabinet cover 25 has been swung back and cover unit 36-37 removed through the 30 open top of the cooling compartment, the supply tank may then also be lifted out. The front and rear walls of the supply tank, as well as one side or end wall, are plane; while the opposite side wall 40 and that portion 41 of the bottom 35 immediately adjacent the front wall are most desirably cylindrically contoured. Said portion 41 is therefore depressed, forming a dipper trough or well vertically below the axis and in the plane of dipper swing, and lower than the flat portion 40 of the tank bottom to the rear, which is sloped gently forward toward the well to cause residual liquid to drain thereinto. That part of the cooling compartment bottom which underlies curved end wall 40 of the supply tank is sloped to conform 50 roughly therewith, as indicated at 40a.

A dipper device, comprising dipper 43 and its unitary hollow stem 44 rigid therewith, depends into supply tank 33, at a location closely adjacent the front wall thereof, from supporting means 55 permitting limited rotational or swinging movement of the dipper device about a horizontal axis perpendicular to the mounting plate 24. The arrangement is such that the dipper device can be swung back and forth to stir the contents 60 of the juice tank, and can also be swung upwardly to elevate said dipper high enough to cause liquid contained therein to flow through its hollow stem 44 and outwardly through the constantly substantially horizontal portion 44a 65 thereof to a convenient exterior point of dispensing delivery. At its delivery end, the hollow dipper stem is provided with an angular discharge spout 44b removably secured thereto as by the bayonet pin and slot connection shown at 44c. 70 Provision is also made for maintaining adequate thermal insulation of the beverage supply tank at this locality despite the necessary aperturing of its front wall to permit passage of the dipper stem therethrough at some distance from the 75 horizontal axis aforesaid. One practical form

which such arrangement may take, as well as typical means for producing the stated swinging movement of the dipper device in the manner and to the extent desired, are shown in the drawings and will now be described in detail.

In the upper, overhanging portion 20a of the cabinet space in front of plate 24, a tube 45 providing a sleeve-bearing support is so mounted that its axis coincides with the horizontal axis, perpendicular to plate 24, about which the dipper device is to have rotational movement. Rigidly secured to said tube 45 adjacent its opposite ends, as by welding, are mounting fins or flanges 45a, so spaced apart as to fit closely between and abut the adjacent faces of bracket 46 secured to and offset from mounting plate 24, and the lower of two front tie strips 47 at the front of the cabinet overhang 20a, when the tube 45 is seated in aligned recesses with which the upper edges of these members are respectively provided. Bracket 46 and tie strips 47, together with vertical transverse flanged bracing plates 48 extending between said strips and plate 24 and secured to both, bracket 46 also being secured to said plates as well as to plate 24, cooperate to provide a stiff supporting framework for holding said bearing support tube 45 rigidly in proper position. The respective tube flanges are firmly secured to bracket 46 and lower tie strip 47 by machine screws 45b passing through apertures 45c in the fins, most desirably elongated to form slots, and cooperating tapped holes in the bracket and tie strip. This arrangement enables any necessary fine adjustment of the alignment of bearing support tube 45.

Press-fitted into bearing support 45 is sleeve bearing 48a, within which turns shaft 49 carrying a sprocket 50, whose hub 51 is fixed thereto as by set screw 52, and one face of which is recessed as indicated at 53 to fit snugly over the end of the sleeve bearing. This arrangement, together with retaining flange 54 secured to the opposite end of the shaft by machine screw 55 which is accessible for adjustment or disassembling upon removal of closure plug 56 of the bearing support tube, prevents longitudinal movement of the shaft within said bearing. On the opposite face of the sprocket hub, which is flush with the adjacent end of shaft 49, is mounted for coaxial rotation therewith, within peripherally sealed circular opening 57, which extends through mounting plate or partition 24 and also through the front wall of refrigerating compartment and the interposed heat-insulating material 29, a circular disk 58 which, in turn, carries the dipper device aforesaid. This disk, which is most desirably composed of a synthetic plastic or other adequately strong and tough heat-insulating material, has its front face recessed, as indicated at 59, to fit over the inner end of sprocket hub 51, and is rigidly secured thereto by machine screws 60 which extend through the disk from its rear face and have their heads countersunk therein.

In order to accommodate and permit the necessary rotational movement of the parts projecting rearwardly from disk 58 and now to be described, the front walls of supply tank 33 and its cover are apertured in proper alignment with said disk, as indicated at 33a and 33b. Notch or recess 61, which extends radially inward from the periphery of disk 58 a distance somewhat greater than the external diameter of the horizontal portion 44a of the dipper stem, and the concave semicylindrical base wall 61a of which

has a radius of curvature slightly greater than half said diameter, is adapted to receive said portion 44a of the dipper stem. Seated in rectangular recess 62 on the rear face of said disk and secured thereto by machine screws 63 which extend through the disk from its front face and have their heads countersunk therein, is the base 64 of a hanger hook which includes a rearwardly projecting outer portion 65 that is rigid with said base and is broadened to provide circularly curved lateral retaining flanges 66, 66a, which are concentric with the aforesaid cylindrical base wall 61a, and which overhang and are spaced from the disk surface as shown (Figs. 10 and 11).

Cooperating with this hanger hook is a dipper bracket and claw member indicated generally at 67 (Fig. 12), which has a flat catch portion 68 slidably seating against portion 65 of the hanger hook, with depending, inwardly directed circularly arcuate lateral flanges 69, 69a, which slidably fit around and under the cooperating arcuate flanges 66, 66a, of the hanger hook. Spot-welded or otherwise rigidly secured to said member 68 is plate 70 which has its end portions bent at right angles to provide two rearwardly extending flat bracket arms 71, 72. The hollow stem of the swingable dipper device is attached to the outer ends of said bracket arms, said ends being arcuately formed to fit closely the contouring of the dipper stem at the points 73, 74, where they respectively engage the stem and are firmly united therewith as by welding; the claw flanges 69, 69a being coaxial with the forwardly extending, substantially horizontal portion 44a of the dipper stem, which is adapted to seat loosely in the semicylindrical inner or base portion of recess or notch 61. The parts are so proportioned and disposed relative to one another that, when the parts are properly assembled with portion 44a of the dipper stem so seated, its longitudinal axis coincides with that of said cylindrical base portion; and said claw flanges 69, 69a, are interengaged with flanges 66, 66a, of the hanger hook.

In order thus properly to assemble the dipper device with the rotary mounting and insulating disk 58, the horizontal portion 44a, with the detachable discharge spout 44b removed, is thrust endwise through notch or recess 61 in the disk periphery until portion 69 of the bracket and claw member carried by the dipper stem is closed to the rear face of said disk. Then, with portion 44a of the dipper stem seated in the base of recess 61, and in such angular position that, viewing the parts as seen in Fig. 10, the circularly curved claw flanges 69, 69a, are somewhat above hook flanges 66, 66a, and are circularly aligned therewith in coplanar relation, the desired sliding interengagement is effected by turning the dipper and mounting claw assemblage counterclockwise about the axis of said portion 44a of the dipper stem. Suitable stop means, such as pin 75, arrests this turning movement when the claw member fully overlies the supporting hook member. At the same time, reverse or clockwise turning movement of said assemblage is prevented by means of a latch device comprising curved spring clip 76 secured at one end 77 to claw flange 69, as by welding, and provided at its free opposite end with a latch pin 78 which works through a hole in said flange and is pressed radially inward by the action of the spring clip. Just as the claw member is about to strike and be arrested by stop pin 75, the latch pin registers with and is forced into a recess 79 provided in the adjacent face

of the cooperating flange 56 of the hook member, thus holding the assembled parts firmly against accidental disengagement. Yet, when it is desired to remove the dipper device, the latch pin is readily moved out of recess 79 by lifting that end of the spring clip; whereupon turning the dipper and mounting claw assemblage clockwise disengages it from the mounting hook and permits removal of the dipper device.

It will be seen that the described arrangement provides a firm and rigid mounting of the dipper device on the disk 58, which at the same time can be readily disassembled, when desired, for cleaning or other purposes. Moreover, the off-center mounting of the dipper device on the disk in the manner described entirely avoids the disadvantages and mechanical difficulties that would be involved in having the hollow dipper stem pass through the disk axially.

Suitable driving means are provided for continuously oscillating the agitating and dispensing dipper device, mounted as described, at a predetermined rate and through a predetermined angular distance, usually an equal distance (e. g. 30°) each side of the vertical or central dipper position; whereby to maintain the beverage liquid, e. g. orange juice, properly agitated. Associated with such driving means is provision whereby, while normally operating in this manner, the driving connections may be altered, either manually or by coin-actuated mechanism, to interrupt the normal agitating action of the dipper and cause the dipper automatically to go through a dispensing or vending cycle wherein it is elevated to dispensing position as shown in dotted lines in Fig. 1, and then returned to its lowered position for resumption of its oscillatory agitating movement. This latter then continues indefinitely until once more interrupted by initiation of another dispensing cycle. While such driving means may take widely differing specific forms within the scope of the invention, the arrangement here illustrated and now to be described works well and has certain advantages of considerable importance from a practical standpoint.

In the specific form here illustrated by way of example, the invention is embodied in apparatus more particularly suitable for use in locations where, as at a soda fountain, an operator is in attendance to serve purchasers with measured portions of the beverage dispensed by the apparatus. Therefore the means here shown for changing the functioning of the dipper device from its normal operation of stirring the beverage to that of dispensing a measured portion of it are manually operable without deposit of a coin. In general, such means comprises clutch mechanism shiftable to connect a normally idle dispensing or vending cycle drive shaft temporarily to a source of power which also actuates an agitating drive shaft, such connection being maintained until a predetermined cycle of dispensing movements has been completed, whereupon the connection is automatically broken.

Located within cabinet 20, therefore, in the space below the sloped portion 40a of the brine tank bottom, is an electric motor 80 of the gear head type, connected by flexible coupling 81 to main driving shaft 82 journaled in suitable bearings on the frame of the transmission gear box or case 83. Shaft 82 drives similarly journaled agitating transmission shaft 84 continuously through meshing gears 85, 86, fast with the respective shafts. In the arrangement here shown, drive shaft 82 revolves counter-clockwise, as

viewed in Fig. 5. Shaft 84 extends through the front wall of the gear case, and to its projecting end is fixed crank disk 87 having crank pin 88. Gear 89, loose on shaft 84 and provided with a hole or holes 90 in its web, constitutes the driven member of a pin clutch, of which the two-part driving member consists of driving collar 91 fixed to said shaft as by set screw 92, and pin-carrying collar 93 longitudinally shiftable on said shaft to move clutch pin 94, which is rigidly mounted on said collar 93, through passage 95 in collar 91 toward or away from gear 89, and the holes 90 therein, any of which said pin is adapted to enter for the purpose of driving said gear. Spring 96, coiled around shaft 84 and compressed between fixed collar 91 and longitudinally movable collar 93, tends to move the latter away from collar 91 into a limiting position such that the clutch pin 94 is just disengaged from gear 89. This limiting position, which is constantly maintained except during a dispensing cycle, is determined by abutment of stop ring 97, seated in a circumferential groove at the free end of a shorter pin 98 secured to collar 93, with shoulder 99 in passage 100 through collar 91 in which this pin works.

Also journaled in the gear case frame and projecting through the front wall of said case is dispensing or vending cycle shaft 101, carrying fast therewith gear 102 which meshes with gear 89 and is desirably of greater diameter. Also fast with shaft 101 is a circular disk 103 having a rearwardly extending peripheral flange 104, whose rear face is formed as a cam track 104a against which bears roller cam-follower 105 trunnioned in and intermediate the ends of a double cross bar or frame 107, as indicated at 106; the assemblage constituting a clutch-shift lever device fulcrumed on the cam flange. This lever device is connected at its ends to shafts 84 and 101 in such manner as not to interfere with rotation of said shafts, and as to be movable longitudinally along the same. In the particular construction here shown, one end of said lever device is pivotally secured at 108 to a squared collar 109 which is loose and slideable on shaft 101. Its opposite end is similarly pivoted at 110 to squared collar 111 which is loose and slideable on shaft 84. Coiled compression spring 112 on shaft 101 is confined between hub 113 of gear 102 and said collar 109, and at all times acts upon the lever device aforesaid to press collar 109 against the hub 103a of cam disk 103, except as hereinafter noted. Furthermore, with the clutch fully engaged as shown in Fig. 4, which depicts the mechanism as being in dispensing phase and as having nearly completed a dispensing cycle, the cam follower 105 is riding on the highest part 115 of the cam track 104a. Also, because spring 112 is stronger or stiffer than clutch-disengaging spring 96, the pressure of collar 111 against collar 93 holds the clutch engaged, against the opposing thrust of spring 96. Upon slight further rotation of the cam, counterclockwise as seen in Fig. 5, the dispensing cycle is completed and follower 105 is pressed into the relatively deep depression 114 in the cam track, causing immediate disengagement of the clutch and cessation of all movement on the part of shaft 101 and the cam disk fixed thereto. Operation in agitating phase is thus restored and continues until another dispensing cycle is started.

In order to start another dispensing cycle, it is necessary to rotate the cam disk farther in the same direction through a sufficient angle to

cause follower 105 to ride up out of depression 114 on to the high part 115 of the cam track, thus elevating the fulcrum of the clutch-shifting frame 107. This forces rearwardly the collar 109 and that end of the frame which is pivoted thereto, thereby increasing the compression of spring 112. If at this instant the clutch pin 94 and one of the clutch holes 90 in gear 89 happen to be in alignment, the opposite end of the frame, with collar 111 pivoted thereto, will be simultaneously moved rearwardly a distance sufficient to cause engagement of the clutch; the thrust of the stronger spring 112 overbalancing that of the weaker spring 96 as aforesaid. However, if the rotating composite clutch member 93-95 happens, at the instant the follower 105 rides up out of the depression 114, not to be in such angular position that the clutch pin 94 and one of clutch holes 90 in the then stationary gear 89 are properly aligned, the clutch pin is in that event simply thrust into abutment with the web of gear 89 and bears thereon until, upon sufficient further rotation of the clutch member 93-95, such proper alignment occurs and the clutch parts engage. In the specific construction here shown, where the gear 89 is provided with a plurality of holes into any of which the clutch pin may enter, the delay in clutch engagement due to initial non-alignment of pin and hole is only momentary. During such delay, collar 109 on shaft 101 is lifted somewhat out of contact with the hub of cam disk 103 against the thrust of spring 112, but upon clutch engagement is again immediately seated on the hub by said thrust. Collars 109 and 111 are sufficiently loose on their respective shafts to permit the described movements to take place.

The clutch being engaged, dispensing shaft 101 is driven, together with dispensing crank 116 fixedly secured to the forward end of said shaft which projects through the front wall of the transmission case. When the dispensing shaft and the cam disk fixed thereto have completed substantially one revolution, follower 105 drops back into recess 114 in the cam track, causing disengagement of the clutch and restoration of the parts to the agitating phase position.

Suitable means are provided for turning cam disk 103 into proper starting position, wherein follower 105 is elevated to cause engagement of the described clutch mechanism and thus initiate the dispensing cycle. In the arrangement here shown, a tripping device for this purpose comprises a bar 117 which is fixedly secured near one end to pivot shaft 118 journaled in the transmission case frame and extending through the front wall of said case and the front wall of the cabinet; an operating lever handle 119 fixed to such externally projecting extension; and a pendant latch hook or catch 120, pivoted to said bar near its opposite end to swing freely therefrom. When dispensing shaft 101 and the parts associated therewith are at rest, said hook is maintained by gravity in latching contact with a detent, such as peg 121, carried on the front face of cam disk 103. For the sake of convenience in explanation, the hook and detent are shown in Fig. 5 as being in this position, in which the cam disk has turned counterclockwise slightly farther than in the position shown in Fig. 4, so that follower 105 rests in depression 114 and the clutch is disengaged.

When the parts are thus positioned, downward pressure on the operating lever handle 119 causes the hook to be lifted to engage peg 121 and ad-

vance the cam disk counterclockwise through a small angle just sufficient to elevate follower 105 and engage the clutch to initiate the dispensing cycle, as above described. Upward movement of tripping or latch bar 117 is limited by suitable stop means to an amount just sufficient to accomplish this result. Upon release of handle 119, the latch bar is returned to its original position by gravity, this return movement being expedited by the downward pull of a coil spring 122, if desired, as here shown.

When, due to initial non-alignment of the clutch pin and a receiving hole in gear 89, completion of clutch engagement is momentarily delayed, pushing down the operating handle 119 may be said to "cock" the dispensing cycle mechanism; so that when the proper alignment does occur, the somewhat increased compression of spring 112 by reason of the temporary lifting of collar 109 from its normal seat against hub 103a of the cam disk, enables that spring to complete more expeditiously its slightly delayed action in perfecting clutch engagement.

In order that, under the conditions just described, the bearing of the clutch pin against the gear web may not cause more or less premature "drifting" movement of gear 89 and the train of dispensing mechanism arranged to be driven thereby, prior to positive driving engagement of the clutch parts, it is desirable to provide a shallow recess or notch 122a in the cam track, into which the follower 105 drops immediately after riding out of the deep recess 114. Recess 122a is so shallow that the elevation of follower 105 is still ample to accomplish the desired engaging movement of the clutch parts for initiating the dispensing cycle; but it is deep enough to provide a detent effective to prevent the aforesaid "drifting" movement and thereby ensure positive start of said cycle at the same definitely established point in each instance. Since the cam track is of uniform height except for the said depressions or recesses 114 and 122a, positive clutch engagement is maintained throughout the further counterclockwise movement of the cam disk through somewhat less than 360°, which is terminated by dropping of the follower 105 into deep recess 114 and consequent disengagement of the driving clutch mechanism.

Just before this return of the dispensing mechanism parts to their normal or inactive position is completed, peg 121 strikes the tail 123 of the latch hook, swings the hook backward about its pivot, and rides over its nose 124. The hook then swings back freely into latching position as the cam disk comes to rest, in which position the hook is ready to engage the peg and re-set the cam for another dispensing cycle, when handle 119 is again depressed.

Referring now to Figs. 1-3 more particularly, a length of roller chain 125 trained about sprocket 50 has one end attached to crank pin 88 of crank 87 on the continuously driven agitator shaft 84, and the other end to a coiled spring 126 which, in turn, is anchored as at 127 to plate 24 or other convenient stationary part of the apparatus. At some suitable point 128, intermediate the sprocket and crank pin 88, another length 129 of roller chain has one end fastened to chain 125; while its other end is secured to crank pin 130 of crank 116 on the normally idle dispensing shaft 101. The respective throws of said cranks 87 and 116, as well as the respective lengths of chains 125 and 129, are all so proportioned and correlated to each other, and the point of attachment

of chain 129 to chain 125 is so chosen, that whatever may be the angular position of either crank, spring 126 is always under greater or less tension, tending to turn sprocket 50 clockwise as viewed in Fig. 1. Hence the spring at all times tends to draw the chain over sprocket 50 and thereby to produce angular movement of the dipper assembly in a direction opposite to that which can be produced periodically by the outward throw of either of the two cranks. Thus, at all times during operation of the machine in the normal agitating (non-dispensing) phase or cycle, each outward throw of crank 87 on the continuously revolving agitator shaft 84 (i.e. in a direction away from sprocket 50) causes sprocket 50 to turn counterclockwise against the pull of spring 126 until, at the outer dead-center position, corresponding to completion of the outward throw of the crank, the dipper has been swung to the position constituting the predetermined end of its agitating swing in that direction (toward the right in this instance). Its position at the end of the agitating swing may be any desired angular distance (e. g. 30°) beyond the mean or central position of the dipper in its agitating swing. In said mean position, that part of the dipper most remote from the axis of swing, i. e. the common horizontal rotational axis of sprocket 50 and disk 58, lies in the vertical plane passing through said axis. In the present instance such part of the dipper is its scooping lip 131, the radial distance of which from the axis of swing is only slightly less than that of the coaxial concave cylindrical bottom surfaces 40, 41, of the juice supply tank 33. Following completion of the outward throw of crank 87, its succeeding inward throw in rotating through another 180°, permits spring 126 to turn sprocket 50 clockwise until the crank has returned to its inner dead-center point, at which point the dipper has been swung back through its mean position to its predetermined limit of swing (e. g. 30°) therebeyond. By the continuous revolution of shaft 84, this alternating to-and-fro agitating movement of the dipper is made to occur at any desired rate which depends, of course, upon the speed at which shaft 84 is driven. A speed of 18 R. P. M. for shaft 84 is typically good practice. The direction of rotation of this shaft as viewed in Figs. 1 and 5, is assumed to be clockwise in this illustrative embodiment of the invention, as already noted. The speed at which shaft 101 is rotated should be relatively slower, in order to avoid loss of any of the measured amount of liquid from the dipper as it is being elevated in the dispensing cycle, and to ensure complete emptying of the dipper through its hollow stem during the period when the dipper is at a level higher than its center of swing. In the present example, the diameter of gear 102 is twice that of gear 89, so that shaft 101 revolves one-half as fast as shaft 84.

During operation of the machine in strictly agitating phase or cycle, the dispensing shaft 101 remains at rest, with its crank 116 in such angular position that connection of its crank pin 130 to chain 125 by chain 129 does not interfere with or otherwise affect in any way the above described reciprocating movement of chain 125 produced by the conjoint action of crank 87 and spring 126. This requirement is met by so setting crank 116 on shaft 101 that, when follower 105 rests in depression 114 of the cam track, crank pin 130 is closest to sprocket 50; which may be called the normal or inactive position of the dispensing crank. Obviously, the effective length of chain 75

129 between crank pin 130 and the point of attachment 128 to chain 125 must be such that, when the dispensing crank is in said normal position, such effective length is at least as great as that of the portion of chain 125 extending between said point 128 and crank pin 88. Contact between the respective chains, except at point 128, may be minimized, if desired, by providing means to hold them apart. For example, tension spring 132 or other resilient member may be connected to an intermediate point of chain 129 and anchored to spring 126 as indicated at 133, to hold the slack of chain 129 clear of chain 125.

The throw of crank 116 is greater than that of crank 87 by an amount such that, when the mechanism performs a dispensing cycle, dispensing crank 116 will take over actuation of the dipper device at a suitable point in the normal or agitating swing of the dipper; and, from that point on, will cause the dipper eventually to travel beyond one limit of its normal or agitating swing and rise, at progressively diminishing speed, to a predetermined maximum height above its axis of swing and discharge its measured content of liquid through its hollow stem. In the specific illustrative embodiment of the invention herein described by way of example, the dipper attains a maximum elevation, at the extreme outward throw of the dispensing crank, such that it then has an effective liquid discharge angle or slope in the neighborhood of 20 degrees to the horizontal. Accordingly the dipper will be in liquid-discharging position, i. e. higher than its axis of swing, long enough to ensure adequately complete emptying and drainage of the measured juice from the dipper to the point of ultimate delivery; especially so because of the virtual "dwell" characterizing its simple harmonic motion while it is higher than its axis of swing.

It will be noted that, in the construction illustrated, the mounting plate 24 is apertured at 134 to accommodate the forward end of the gear box or case 83, the outer front wall of which is flush with said mounting plate and is suitably held in position as by mounting straps 135 fastened both to the plate and to the frame of the gear case by cap screws 135a. At the rear, the gear box is similarly secured by cap screws 136 to vertical supporting plate 131 which has an integral base flange anchored to the floor of the cabinet as indicated at 138.

The front panel of the cabinet is removable, by turning out screws 139 which hold it in place, for inspection and adjustment of the operating parts housed in the forward compartment between said panel and mounting plate 24. An opening closed by removable cover 140 is provided in the end wall adjacent the motor and gear box for ready access to these parts. It is to be understood that suitable means (not shown) may be provided for preventing unauthorized access to the interior of the cabinet in any manner, whether by removal of the removable cabinet portions mentioned, or otherwise.

The operation of the apparatus here shown will be readily understood from the foregoing description, but will be briefly summarized, as follows: Assuming the supply tank 33 to be filled with orange juice, for example, and the motor 80, as well as the motor of the refrigerating unit 23, to be connected to a suitable electric power line, and further assuming the transmission mechanism to be in the position illustrated in Fig. 4, the dispensing cycle is nearly concluded and follower 105 is about to drop into cam de-

pression 114 and render shaft 101 idle. The continuous rotation of shaft 84 thereupon causes dipper 43, which is in its depending or lowered position, to resume its back-and-forth swinging movement through a limited angular distance on either side of the vertical, whereby to maintain the juice in the supply tank continuously agitated. Crank pin 130 being at the extreme inward end of its throw, that is, the minimum possible distance from sprocket 50, chain 129 is now loose, while the entire length of chain 125 is constantly taut and therefore reciprocated by rotation of crank 87 against the resisting tension of spring 126. When it is desired to dispense a measured portion of the juice, lever handle 119 is depressed to shift cam 103 into starting position, thereby causing engagement of the transmission clutch and rotation of shaft 101 and cam disk 103 through one dispensing cycle as previously described. Due to the relative proportioning of the respective throws of cranks 116 and 87, and of the lengths of the respective chain sections described, the continuous rotation of agitating crank 87 ceases to have any effect upon or control over the movements of the dipper shortly after commencement of the dispensing cycle, because the angular movement of crank 116 thereupon causes chain section 129, and that section of chain 125 between point 128 and the spring 126, to be tensioned directly by crank 116, the remaining loose section of chain 125 remaining idle during the dispensing cycle despite the uninterrupted rotation of crank 87. The oscillatory movement of the dipper is thus discontinued at a predetermined angular position of crank 116. By the further action of crank 116, the dipper is first raised to its position of maximum elevation as shown in Fig. 1, wherein it discharges its measured content of juice through the dipper stem 44—44a and removable angular discharge nozzle 44b downwardly through stationary delivery funnel 141 into a paper cup or the like 142 standing on shelf 143. Then, as crank 116 passes its point of maximum outward throw and returns to its normal position of rest, the action of spring 126 rotates sprocket 50 and mounting disk 58 clockwise until the dipper is again in its lowermost position and, from then on is again continuously oscillated back and forth by the resumed action of crank 87, the agitation phase being thus re-established.

All parts of the apparatus coming in contact with the beverage to be dispensed should most desirably be made of stainless steel or other material suitably resistant to corrosion or discoloration. Such parts include, for example, the beverage supply tank and its cover, the dipper device, the rotary mounting disk, and the means for mounting the dipper on said disk.

It is desirable that the dipper member proper shall be so designed and constructed that, in addition to being adapted to function effectively as means for stirring or agitating the beverage liquid in the supply tank, it may also, at all times when a dispensing or vending cycle is being performed, measure out and dispense approximately the same amount of liquid from said tank, whether the level of the liquid in the tank is relatively high or relatively low. The specific form of dipper 43 here illustrated has important practical advantages in this connection. As shown, it comprises a receptacle that is generally rectangular in plan and open on the side that is uppermost in dispensing position of the dipper. A tapered tubular adapter or funnel connection 144 unites the

dipper with its hollow stem 44. Viewed in side elevation, the dipper is seen to consist of two angularly disposed sections, one of which has its side walls 145 and bottom 146 extending parallel with the axis of dipper stem 44; while the side walls 147 and bottom 148 of the other sections extend at right angles thereto. The latter section is open at its outer end, thus constituting in effect a scoop whose lip 131 clears the curved bottom of dipper trough or well 41 by a relatively small distance as the dipper device swings. Furthermore, the transverse width of the dipper is not greatly less than that of said dipper trough. Consequently, when swinging back and forth through the dipper trough or sump while the mechanism is operating in agitating phase, this scoop section of the dipper acts somewhat like a pump plunger, forcing liquid ahead of it in opposite directions alternately, and thus, apart from the agitation produced by the rest of the dipper structure, is especially effective in preventing settlement of suspended solids and in helping to maintain the entire body of liquid in the supply tank turbulent to the extent desired.

Moreover, even though the level of the liquid in the supply tank may be relatively low, the described dipper construction and its mode of operation are such as to ensure that, in a dispensing or vending cycle, more liquid will be scooped up and momentarily carried above the liquid level by the dipper than the predetermined quantity which it is desired to dispense. In order that this predetermined desired quantity may be automatically measured out with reasonable accuracy in each dispensing operation of the dipper, the free edge of each side wall 145 of the dipper section nearest the hollow dipper stem is provided with an overflow notch 149, which is most desirably located substantially at the junction of said wall with wall 147 of the scoop section. After the ascending dipper emerges from the body of liquid in the tank, and before the dipper stem 44 has attained a horizontal position, excess liquid spills out through the overflow notches 149, the thus measured remainder being thereafter dispensed when the dipper, in its further ascent, has attained the necessary elevation.

In the particular embodiment of the invention shown in the drawings and hereinabove described in detail by way of illustrative example, the web of gear 89, constituting the driven member of the clutch transmission for actuating the dispensing or vending shaft 101 has a plurality of apertures adapted to be entered by the clutch pin of the driving member; in this way providing for more rapid response to depression of the vending cycle starting lever 119 than would usually be realized if there were only one such aperture. Such an arrangement is entirely satisfactory where the dipper and dipper sump are of such ample size that, even when the liquid level in the supply tank approaches the operative minimum, the dipper will fill sufficiently regardless of the position within its agitating arc of swing from which it starts its vending cycle movement. However, where space is a critical factor necessitating use of a smaller dipper and dipper sump, it is of advantage to provide against the dipper's having to commence to move in dispensing cycle at a point within its agitating arc too close to that end of said arc which is nearest the point of dispensing delivery. To this end, the arrangement may be such, for example, that the dipper can start to move in dispensing cycle only from substantially that end of its agitating arc which is farthest

from the point of dispensing delivery. This may be accomplished by providing only a single aperture 90 in the web of gear 89 for clutch pin 94 to enter; and by so adjusting the angular setting of gear 89 on shaft 84 that the clutch pin can enter said aperture only at an instant when the crank 87 has just completed its inward throw relative to sprocket 50. Obviously, the start of the dispensing movement of the dipper can be fixed at any other selected point within its agitating arc of swing by suitably varying the described timing adjustment.

What is claimed is:

1. Liquid dispensing apparatus comprising, in combination, a liquid supply container, a dipper device mounted to swing therewith about a substantially horizontal axis, a source of power, driving means, including variable transmission mechanism, connecting said source of power with said dipper device, adapted and arranged normally to oscillate the same continuously through a limited arc of swing, normally idle means operable in a dispensing cycle to vary said transmission mechanism and thereby cause the dipper device to swing beyond said arc and upwardly into dispensing position higher than said axis and then to return to said limited arc of swing, and means to actuate said normally idle means.

2. Liquid dispensing apparatus as defined in claim 1, wherein said transmission mechanism comprises a continuously driven shaft for producing the oscillatory movement of said dipper device, a normally idle shaft for producing the dispensing movement, means including engageable clutch members for connecting the two shafts, and means for effecting engagement of said clutch members.

3. Liquid dispensing apparatus as defined in claim 1, wherein said transmission mechanism comprises a continuously driven shaft for producing the oscillatory movement of said dipper device, a normally idle shaft for producing the dispensing movement, means including engageable clutch members for connecting the two shafts, and cam means rotatable with the normally idle shaft and operable to effect engagement and disengagement of said clutch members.

4. Liquid dispensing apparatus as defined in claim 1, wherein said transmission mechanism comprises a continuously driven shaft for producing the oscillatory movement of said dipper device, a normally idle shaft for producing the dispensing movement, means including engageable clutch members for connecting the two shafts, and cam means rotatable with the normally idle shaft and operable to effect engagement and disengagement of said clutch members, the active cam surface being so formed as to maintain the clutch members engaged except during a small part of one revolution of the normally idle shaft.

5. Liquid dispensing apparatus comprising a liquid supply container, a dipper device including a dipper having a hollow stem, means mounting said dipper device for swinging movement about a horizontal axis, with the dipper and an adjacent portion of said stem normally depending into said container, means continuously urging the dipper toward one limit of normal swing, power means operable continuously to move the dipper periodically toward the other limit of normal swing against the opposition of the first means, and further means, connectable at will to said power means whereby, for a cycle of predetermined duration, said power means is operable to

swing said dipper beyond said other limit and into liquid-dispensing position.

6. Liquid dispensing apparatus comprising a liquid supply reservoir, a dipper device including a dipper having a hollow stem, a mounting member supported for rotational movement about a horizontal axis, means securing said dipper device to said mounting member with the dipper and an adjacent portion of said stem depending into said reservoir, a driving sprocket secured to said mounting member, a chain trained around said sprocket and secured at one end to a tension spring which constantly exerts a pull thereon, a motor, a crank shaft arranged to be continuously driven by said motor, a crank on said shaft to which the chain is connected, the rotation of said crank normally causing, in conjunction with said spring, oscillatory movement of said sprocket and said dipper device through a limited angle; a normally idle shaft, a crank thereon to which said chain is also connected and which has a greater throw than the first mentioned crank, clutch means engageable to connect the continuously driven shaft with the second shaft for driving the latter, and clutch shifting means operable to cause engagement of said clutch means and driving of said second shaft for a predetermined period, during which the crank thereon pulls on the chain to turn said sprocket through a greater angle and thereby swing said dipper device up into dispensing position; said clutch shifting means acting automatically to disengage said clutch means after the dipper device has swung down into normal position.

7. Liquid dispensing apparatus as set forth in claim 6, which includes speed reduction gearing between said shafts, whereby said normally idle shaft when driven, revolves more slowly than the continuously driven shaft.

8. Liquid dispensing apparatus as defined in claim 1, wherein said transmission mechanism comprises a continuously driven shaft for producing the oscillatory movement of said dipper device, a normally idle shaft for producing the dispensing movement, means including engageable clutch members for connecting the two shafts, cam means rotatable with the normally idle shaft and operable to effect engagement and disengagement of said clutch members, and means for rotating said cam and the idle shaft from clutch disengaging position into clutch engaging position and thereby initiating a dispensing cycle.

9. Liquid dispensing apparatus as defined in claim 1, wherein said transmission mechanism comprises a continuously driven shaft for producing the oscillatory movement of said dipper device, a normally idle shaft for producing the dispensing movement, means including engageable clutch members for connecting the two shafts, cam means rotatable with the normally idle shaft and operable to effect engagement and disengagement of said clutch members, the active cam surface being so formed as to maintain the clutch members engaged except during a small part of one revolution of the normally idle shaft, and means for rotating said cam and the idle shaft from clutch disengaging position into clutch engaging position and thereby initiating a dispensing cycle.

10. Liquid dispensing apparatus comprising, in combination, a liquid supply reservoir, a mounting member mounted for rotational movement about a horizontal axis and provided with an aperture located at a distance from said axis, a

75

dipper having a stem with a portion remote from the dipper bent at right angles and pivotally seating in said aperture, arcuate attaching members, one secured to said mounting member and another to the dipper stem intermediate the dipper and such pivotally seating bent portion and concentric therewith, said arcuate members being formed for sliding interengagement or disengagement upon appropriate pivoting movement of the dipper and, when interengaged, anchoring the dipper structure to said mounting member.

11. Liquid dispensing apparatus as set forth in claim 6, wherein said clutch means comprises a pin-carrying member secured to the continuously driven shaft and longitudinally movable thereon, a gear loose on said shaft and apertured to receive the clutch pin, resilient means tending to maintain the pin-carrying member disengaged from said gear, a gear fast with said normally idle shaft and meshing with the first mentioned gear, a clutch-shifting lever slidably attached to both shafts and adapted, when suitably actuated, to move said pin-carrying member against the opposition of said resilient means into clutching engagement with the loose gear, a cam member fast with said normally idle shaft and having a circular cam track, a roller cam follower trunnioned on said clutch-shifting lever intermediate the ends thereof and bearing against said cam track, resilient means restraining movement, away from said cam member, of that end of said lever which is secured to the normally idle shaft, said cam track having a depression of such depth that, when said cam member is in such angular position that said follower rests in said depression, the clutch parts are disengaged, while at all other angular positions of the cam member, the clutch parts are engaged; and means for turning said cam member in the proper angular direction to cause said follower to ride up out of said depression and effect clutch engagement for a period corresponding to the remainder of a single revolution of the normally idle shaft.

12. Liquid dispensing apparatus as set forth in claim 11, wherein said cam track is provided with a shallow depression of slight angular extent, closely adjacent the first mentioned relatively deep depression, into which the cam follower drops upon riding up out of the deeper depression; said shallow depression maintaining the cam follower still sufficiently high to ensure clutch engagement, but serving to prevent drifting movement of the cam in event of temporary non-alignment of the engaging clutch parts.

13. Liquid dispensing apparatus comprising, in combination, a liquid supply container, a dipper device mounted on a transverse axis located directly above said container so as to depend thereinto, power means, a first normally continuously operating means connected between said power means and said dipper device to continuously oscillate the latter through a limited arc passing through a transverse vertical plane extending through said axis, the extent of oscillation being sufficient to agitate liquid in said container but not sufficient to move said device above a horizontal plane extending through said axis, a second normally idle means connectable between said power means and said dipper device to take over operation of said dipper from said first means and to swing the dipper beyond one end of its normal arc into dispensing position above said horizontal plane whereby a dispensing cycle is performed and then return it for continued normal operation by said first means, and actuating means

operable to connect said second normally idle means to said power means for performance of one such dispensing cycle.

14. Liquid dispensing apparatus comprising, in combination, a liquid supply container, a dipper device mounted on a substantially horizontal axis directly above said container to swing therewithin, said dipper device including a dipper having a unitary hollow stem rigid therewith which comprises a portion, remote from the dipper, extending substantially at right angles to the portion adjacent the dipper, the said horizontal axis being parallel to but spaced from said remote portion of the stem, said dipper passing close to the container bottom at the lowest point of its swing, and means for continuously swinging said dipper about said axis to an extent sufficient to agitate liquid in said container and means manually initiated at will for elevating said dipper sufficiently to discharge its content of liquid through said hollow stem to a point of delivery outside said container.

15. Liquid dispensing apparatus comprising in combination, a liquid supply reservoir having a bottom and vertical side walls, said bottom being formed with a well adjacent one of said side walls, a mounting member supported for rotational movement about a horizontal axis, a dipper member having a hollow unitary stem rigid therewith and having a horizontal right angle portion at a substantial distance from the dipper, means securing the dipper stem to said mounting member with the horizontal portion extending therethrough and with the dipper normally depending into the reservoir well, the horizontal portion of its stem extending away from said reservoir substantially parallel to said horizontal axis but at a distance therefrom.

16. In a liquid dispensing apparatus having a cooling chamber with an apertured heat insulating vertical wall and a liquid supply reservoir therein, a circular disk of heat insulating material substantially closing the aperture and supported for rotational movement by means wholly outside said chamber, a dipper device mounted upon said disk to swing with the rotational movement thereof and normally depending into said reservoir, and driving means for normally imparting continuous oscillatory rotational movement to said disk between limits suitable to effect agitation of liquid in the reservoir by said dipper device, but also operable at will through a cycle of predetermined duration to extend rotational movement of said disk beyond one of said limits sufficiently to swing said dipper device into liquid dispensing position.

17. In a liquid dispensing apparatus having a cooling chamber with an apertured heat insulating vertical wall and a liquid supply reservoir, a circular disk of heat insulating material substantially closing the aperture and supported for rotational movement by means wholly outside said chamber, a dipper member having a hollow unitary stem with a right angle portion formed by a rectangular bend at a substantial distance from the dipper, means securing the dipper stem to said disk to swing with the rotational movement thereof, with the dipper normally depending into said reservoir, and with the right angle portion of its stem beyond said bend extending outwardly through an aperture in said disk to a place of liquid delivery, and driving means for normally imparting continuous oscillatory movement to said disk between limits suit-

19

able to effect agitation of liquid in the reservoir by said dipper member, but also operable at will through a cycle of predetermined duration to extend rotational movement of said disk beyond one of said limits sufficiently to swing said dipper high enough to discharge liquid through its hollow stem to said place of delivery.

18. Liquid dispensing apparatus comprising, in combination, a liquid supply reservoir, a dipper device including a dipper member and a hollow stem secured thereto, means mounting said dipper device for swinging movement within said reservoir about a horizontal axis and through an arc of sufficient extent to include a dipper position higher than said axis for discharge of liquid from said dipper member into and through said hollow stem to a place of delivery; said dipper member comprising angularly disposed sections one having side walls and a bottom parallel with the axis of the stem and the other having side walls and a bottom continuous with and at right angles to the first section, at least one side wall

10

15

20

20

of said first section being formed with an overflow notch.

19. Liquid dispensing apparatus as set forth in claim 18, wherein at least one overflow notch in the side walls of said dipper is located adjacent the junction of the angularly related portions thereof, to aid in more accurately predetermined the quantity of liquid measured out and dispensed by the dipper device.
